CLAIM

The ornamental design for an optical aiming device, as shown and described.

DESCRIPTION

FIG. 1 is a top perspective view of an optical aiming device showing my new design;

FIG. 2 is a front side view thereof;

FIG. 3 is a back side view thereof;

FIG. 4 is a left side view thereof;

FIG. 5 is a right side view thereof;

FIG. 6 is a bottom view thereof;

FIG. 7 is a top view thereof; and,

FIG. 8 is a top perspective view of an optical aiming device in an environmental use configuration with a mount.

The broken lines depict portions of the optical aiming device that form no part of the claimed design. The broken lines in FIG. 8 that depict the environment of a mount forms no part of the claimed design.

1 Claim, 8 Drawing Sheets
